US00D993639S

(12) United States Design Patent (10) Patent No.: US D993,639 S
Whitty (45) Date of Patent: * Aug. 1, 2023

(54) SHEET MATERIAL

(71) Applicant: Shawna Simmons Whitty, Wilmington, NC (US)

(72) Inventor: Shawna Simmons Whitty, Wilmington, NC (US)

() Term: 15 Years

(21) Appl. No.: 35/513,664

(22) Filed: Dec. 29, 2021

(80) Hague Agreement Data

Int. Filing Date: Dec. 29, 2021

Int. Reg. No.: DM/218830

Int. Reg. Date: Dec. 29, 2021

Int. Reg. Pub. Date: Feb. 18, 2022

(51) LOC (14) Cl. 05-06

(52) U.S. Cl.

USPC D5/63

(58) Field of Classification Search

USPC ..... D6/575, 580, 582, 583, 588, 592, 601, D6/602, 604, 605, 608, 610, 611, 613, D6/617; D5/7, 37, 43, 44, 55, 56, 57, 58, D5/59, 60, 61, 62, 99; D25/128 CPC A47C 31/11; A47C 27/08; A47C 27/14; A47G 27/00; A47G 27/02; A47G 27/04; A63B 37/0023; B60N 2/60; B44F 7/00; B44F 5/00; B44F 3/00; D03D 15/65; D03D 1/02; D03D 1/06; D03D 3/005; D03D 3/0082; D03D 27/02; D03D 15/46
